DIAL FOR CHARTS OR THE LIKE

Filed March 19, 1931

Inventor

SAMUEL SMITH,

By

Samuel Smith Attorney

UNITED STATES PATENT OFFICE

**SAMUEL SMITH, OF BROOKLYN, NEW YORK, ASSIGNOR TO DISK-O-KNOWLEDGE, INC.,
OF NEW YORK, N. Y.**

DESIGN FOR DIAL FOR CHARTS OR THE LIKE

Application filed March 19, 1931. Serial No. 39,143. Term of patent 14 years.

To all whom it may concern:

Be it known that I, **SAMUEL SMITH**, a citizen of the United States, residing in Brooklyn, county of Kings and State of New York, have invented a new, original, and ornamental Design for a Dial for Charts, or the Like, of which the following is a specification, reference being had to the accompanying drawing, forming part thereof.

The figure illustrated in the accompanying drawing is a face view embodying my new design.

I claim as my invention:

The ornamental design for a dial for charts, or the like substantially as shown.

SAMUEL SMITH.
